H. B. CLYATT

TIME SWITCH

Filed Nov. 28, 1924

UNITED STATES PATENT OFFICE.

HARRY B. CLYATT, OF GRAND RAPIDS, MICHIGAN.

TIME SWITCH.

Application filed November 28, 1924. Serial No. 752,734.

The invention primarily aims to prevent the rapid consumption of tubes and batteries in radio receiving sets and to obviate the necessity of an attendant to operate the set 5 in order to cut off the current and restore the same at periods in order to receive items of interest broadcasted from a given station.

The invention combines with an ordinary 10 clock, either as a part thereof or as an attachment, means whereby the circuit of a radio receiving set is closed periodically and which provides for varying the length of contact according to the news items to be 15 received.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without 25 departing from the nature of the invention.

Referring to the accompanying drawings forming a part of the specification,

Figure 1 is a front view of a clock provided with circuit closing means embodying 30 the invention.

Figure 2 is a side view illustrating the circuit in diagram, and

Figure 3 is a sectional detail on the line 3-3 of Figure 1.

Corresponding and like parts are referred to in the following description and designated in the several views of the drawings by like reference characters.

The numeral 10 designates a clock which 40 may be of any approved construction, the same being illustrated to demonstrate the application of the invention. The numeral 11 denotes a support of insulating material such as hard rubber, the same being preferably of annular form and secured to the frame of the clock in any convenient and

substantial way as by means of brackets 12 which are bolted to the support 11 and to the frame of the clock. The support 11 is formed with recesses 13 in its outer face to receive plates 14 which are adapted for radial adjustment and which are secured in the required adjusted position by binding screws 15. A metal ring 16 is placed against the outer side of the support 11 and is secured thereto by means of screws or like fastenings 17 and this ring 16 constitutes an annular contact which is provided at diametrically opposite points with inwardly disposed and depressed extensions 18 projecting into the path of the minute hand 19 of the clock so that when the minute hand engages either parts 18 or any one of the plates 14 when adjusted inwardly 55 closes the circuit of the radio receiving set 60 so that the news broadcasted from a given station will be received and amplified so as to be heard by listeners in. In the preferable arrangement the clock and the annular or ring contact 16 are included in the 70 filament circuit of the radio receiving set as indicated in Figure 2 so that when the minute hand 19 engages either extension 18 of the contact 16 or any one of the plates 14 when adjusted inwardly the filament circuit of the set will be closed and reception 75 effected.

What is claimed is:

An automatic circuit closing attachment comprising a support of insulating material 80 provided in a side with recesses, a contact ring fitted to the side of the support having the recesses and extending over the latter, and provided with inwardly disposed extensions, contact plates within the recesses 85 of said support and in electrical connection with the contact ring and radially adjustable, and means for securing the contact plates in the required adjusted position.

In testimony whereof I affix my signature.

HARRY B. CLYATT,
